UNITED STATES PATENT OFFICE.

JOHN JACOBY AND BRONO WIECZORKIEWICZ, OF CLEVELAND, OHIO.

DESIGN FOR A LAMP SHADE.

Application filed December 20, 1926. Serial No. 20,103. Term of patent 14 years.

To all whom it may concern:

Be it known that we, JOHN JACOBY and BRONO WIECZORKIEWICZ, citizens of the United States, residing at Cleveland, in the county of Cuyahoga and State of Ohio, have invented a new, original, and ornamental Design for Lamp Shades, of which the following is a specification, reference being had to the accompanying drawing, forming a part thereof.

The drawing is a perspective of the lamp shade which may be mounted on any suitable base.

We claim:

The ornamental design for a lamp shade substantially as shown.

JOHN JACOBY.
BRONO WIECZORKIEWICZ.
